DEVICE FOR FORMING SOUND RECORDS

Otto Wittel, Rochester, N. Y., assignor to Eastman Kodak Company, Rochester, N. Y., a corporation of New Jersey

Application July 2, 1946, Serial No. 680,929

4 Claims. (Cl. 274—3)

1

The present invention relates to recording, and more particularly to sound recording.

The principal object of the invention is the production or formation of a sound-reproducing record from images of a sound wave or combinations of such waves.

Still another object of the invention is the provision of a sound reproducing member or record on which the individual sound records or waves are recorded as continuous sound circles, each circle being independent of the other sound circles.

Yet another object of the invention is the provision of an apparatus and a method for producing sound-reproducing records from separate film strips, each strip having a single continuous sound record thereon.

To these and other ends, the invention resides in certain improvements and combinations of parts, all as will be hereinafter more fully described, the novel features being pointed out in the claims at the end of the specification.

In the drawings:

Fig. 1 is a vertical sectional view showing one arrangement for producing a record from a film strip having a continuous sound record or wave image formed thereon;

Fig. 2 is a view of one of the sound-bearing film loops from which the record is produced or formed;

Fig. 3 is a view similar to Fig. 1, but showing another form of sound record formed from the film loop illustrated in Fig. 2;

Fig. 4 is a partial view of the apparatus shown in Fig. 3 showing still another method of reproducing the sound records from the film loops on to a disk; and

Fig. 5 is a view of the light slit through which a beam of light is directed onto the film loop to project a small increment of the sound record thereof onto the receiving member or disk.

Similar reference numerals throughout the various views indicate the same parts.

The present invention relates to a method and apparatus for forming sound records from photographic images of a continuous sound. The sound may be that of a musical note, either with or without its harmonics, but it may also be any continuous sound or vibration periodically repeated but which may vary in amplitude, frequency, and/or form. If the sound to be recorded is a musical note, this note is produced, preferably by an outstanding musician, so as to secure a true and proper note. The vibration resulting from the production of such a note is then

2

recorded on a master or original strip of photographic material in the usual well-known manner. This film strip is then cut to a predetermined length such, for example, as that representing one second of time, checked for correct pitch, and then the free ends thereof are spliced together to form an endless loop or band. If necessary, the sound record may be retouched at the splice so as to provide a continuous unbroken record of the note or sound which may be repeated one or more times around the loop. Various such loops are formed, each loop having a single continuous and unbroken image of the sound wave representing a single musical note or sound. Thus a separate loop will be necessary for each note or sound. These separate loops are then brought successively into the path of a light beam which progressively projects small increments of the image thereof onto a suitable receiving member of disk form which reproduces the image of each loop as a continuous unbroken sound image circle on the record or disk. The image of each loop is thus reproduced as a continuous sound image circle, the circles being independent and spaced radially and concentrically on the disk. This reproduction may be accomplished optically, electromagnetically, or mechanically, as will be later more fully described.

Fig. 2 shows one of the master or original strips 11 which is in the form of a photographic film, and has the musical note or sound record 12 formed thereon. The strip 11 is cut to proper length, preferably one second of time, and, after checking for pitch, is arranged in a loop with the ends 13 abutting. These ends are then joined or spliced together, in any suitable well-known manner, to maintain the strip in a loop form, as shown in Fig. 2. The splice is preferably made at the dense part of the wave so that it can be touched up so as to continue the true wave form across the splice, as shown at 14, Fig. 2. Thus each loop of film carries a continuous and unbroken photographic image of a musical note or continuous sound, as is apparent from an inspection of Fig. 2. This film loop with its sound image or record can then be utilized to form a duplicate sound record on a disk or similar reproducing member.

To secure this result, an image-receiving disk 17 is positioned on the top surface 18 of a turn-table 19. A drive shaft or spindle 20 is connected to the turn-table and extends through a registering hole 21 of the disk so that upon rotation of the spindle the turn-table and disk will 55 rotate as a unit, as is apparent. The turn-table

19 is provided with an upstanding marginal annular flange 22 on which the loop of film 11 may be placed. The height of the flange is slightly less than the width of the film 11 so that the image carrying portion 12 of the film 11 will extend above the top of the flange, as shown in Figs. 1 and 3. The lower edge 23 of the film rests on and is supported by a lip or shoulder 24 of the turn-table. Thus the film loop and the disk 17 are supported on the turn-table 19 and will turn as a unit and in absolute synchronization upon rotation of the turn-table.

In the arrangement shown in Fig. 1, the disk 17 comprises a transparent base 25, such as glass, the upper surface of which is coated with a sensitized light-sensitive emulsion 26. With this arrangement, the sound image 12 on the strip 11 is transferred to the disk 17 by optical means. To secure this result, a light source, such as an electric lamp 30 is positioned to the left of the film loop and in horizontal alignment with the sound portion 12 thereof. A condenser lens 31 and a plate 32 having a narrow light slit 33 are positioned between the lamp 30 and the film loop, as clearly shown in Fig. 1.

The objectives 34 and 35 throw an image of the slit 33 onto the record 17 with the help of prism 36, as will be readily apparent to those familiar with the photographic and optical arts.

When the turn-table 19 is rotated, the disk and the film loop are rotated as a unit and in absolute synchronism. During such rotation, the optical members are stationary so that successive increments of the sound record 12 of the film loop are progressively passed across the narrow light slit 33 so that the sound record 12 is progressively imaged on the emulsion 26 to form a complete latent image of the sound record 12. This image will, as is apparent, be in the form of a continuous unbroken circle, as is the case of the sound record 12 of the original film strip 11.

Thus the sound record 12 has been reproduced on the disk 17 as a continuous unbroken circle of the image of a single sound or musical note.

When one of such sounds or notes has been thus recorded, the film loop is removed and replaced by another film loop which contains a different sound record or another musical note. In order that the sound record of this second loop may be recorded on the emulsion 26 of the disk 17, the objectives 34, 35 and prism 36 are refocused so as to direct the recording beam of light to a point radially spaced from the previously recorded sound circles. The turn-table is again rotated to record the sound image of the second film loop as a second sound circle on the emulsion 26 of the disk 17. This procedure is continued until the desired number of sound records or circles have been recorded. These sound records will be in the form of separate spaced and concentric circles on the disk 17, each circle being a continuous and unbroken record of a single sound or musical note. In order to secure uniform illumination and to avoid steps in the printed or recorded sound circles on the disk 17, the printing of each loop is done over a great number of revolutions, and the light source is gradually increased and gradually decreased during the recording operation.

On a 12-inch record or disk 17, about forty separate sound records or circles may be reproduced or printed. For reproducing a full piano scale probably two such records would be required, while for other instruments, such as the violin, only one such record might be necessary.

However, for some instruments having a very limited scale, such as a flute, several such instruments might be recorded on a single record. The making of such a master record or disk 17, is somewhat lengthy and costly, but once made, any desired number of duplicates can be made by printing or other methods. Such duplicates will be an exact reproduction of disk 17, and will contain a plurality of separate and distinct concentric circles, each of which constitutes a single continuous and unbroken sound record or musical note.

In the arrangement shown in Fig. 3, the reproduction of the film loop is accomplished electro-magnetically. In this embodiment, the record receiving disk comprises a base 39 of a non-magnetic material on which are arranged a plurality of separate concentric rings 40 of a magnetic material such, for example, as steel. This disk may be made in several ways. For example, a steel disk can be soldered, welded, or otherwise secured to the non-magnetic base 39 and grooves can then be cut through the steel disk leaving separate steel rings. On the other hand, magnetic materials can be deposited by electro-plating in rings on a non-metallic base. Or, grooves can be cut in the non-magnetic base, and these grooves can be filled with a powdered magnetic material and sintered. In any event, the non-magnetic base has formed or produced thereon separate concentric rings of a magnetic material, and is positionable on the turn-table 19 so as to rotate as a unit therewith and with the film loop in the same manner as the arrangement shown in Fig. 1 and above described.

In this embodiment, a prism 41 directs the light from a lamp 42 to the lens 31 and the slit 33 of the plate 32 and onto the sound record 12 of the film loop carried by the turn-table. The light rays which pass through the sound record 12 are directed towards a light-sensitive element such as a photo-electric tube 43 or other similar element which is affected by light variations. This tube is connected by leads 44 to an amplifier 45 which, in turn, is connected by wires 46 to a source of power, not shown. Leads 47 connect the amplifier to a coil 48 which serves to energize and magnetize a member 49 having spaced fingers or pole pieces 50 positioned on opposite sides of one of the rings 40. These fingers serve to magnetize the particular ring in accordance with the particular variations of the light of the tube 43. Thus the magnetizing of the ring 40 is in accordance with the sound records 12. As the latter is rotated past the stationary slit 33, the sound record 12 is progressively reproduced magnetically on the ring 40 as a continuous and unbroken sound record identical to the record 12. Additional sound records are subsequently reproduced on the various rings 40 by changing film loops and moving the member 49 to bring the fingers 50 thereof in cooperating relation with different rings 40. Thus each ring 40 has impressed or formed thereon a magnetic record of a single musical note or sound record. Here again, the reproduction is done over a number of revolutions and the light intensity first increases and then decreases.

In the embodiment shown in Fig. 4, the coil 48 is wrapped around magnet 52 with spaced poles 54 between which is positioned a vibrating member 55 which carries a stylus 56 adapted to cut a groove in the surface 57 of the reproducing disk 17, which, in this case, may be made of any suitable material similar to that used to make phono-

graph records. In this arrangement, the sound record 12 and the various film loops are reproduced as separate circular grooves in the surface 57. These grooves differ from the well-known phonographic grooves in that they are separate and distinct circles, while the phonographic record sound groove is in the form of a continuous spiral. However, each circular groove is an exact reproduction of the sound record of one of the film strips or loops from which it was reproduced. Duplicates of such a master record can be made in the same manner as now employed in making duplicate phonograph records from a master. Thus a number of duplicates can be formed for use in connection with sound reproducing mechanisms in which a stylus runs in the various sound grooves or circles.

The present invention thus provides an arrangement by which a plurality of separate continuous sound records or musical notes may be reproduced on a single record in the form of separate, independent, and distinct circles, each circle constituting a single continuous sound record of a musical note or suitable combinations thereof. Duplicates of these records are adapted for use in suitable sound reproducing mechanisms in which the various sound circles may be selectively connected to the reproducing mechanism so as to be reproduced thereby to form a complete musical note or sound record. In this way, various musical instruments may be recorded and reproduced. The reproduction mechanism constitutes no part of the present invention and accordingly is not illustrated or disclosed. The present invention relates to only the formation of the master record or disk from which a plurality of sound duplicates may be formed for use in the sound reproducing mechanism. However, as the original sound record 12 may be made by a skilled musician the desired quality of the notes can be recorded on the disk and the same quality note can then be reproduced by a less skilled musician and even by a novice. Thus, an ordinary person can reproduce the same quality of musical note as originally recorded by the skilled musician.

While certain embodiments of the invention have been disclosed, it is to be understood that the inventive idea may be carried out in a number of ways. This application is, therefore, not to be limited to the precise details disclosed, but is intended to cover all variations and modifications thereof falling within the scope of the appended claims.

I claim:

1. A device for forming a sound-reproducing record comprising, in combination, a strip of photographic film arranged in the form of a loop and having formed thereon a continuous unbroken sound track, a turntable, an annular rim on said turntable for supporting said loop with the record thereof overhanging said rim, a member positioned on said turntable, said turntable being rotatable to move said strip and member in unison, and means for scanning said track and to direct the scanned image toward said member for progressively reproducing the track on said strip in

the form of a continuous unbroken image circle on said member.

2. A device for forming a sound-reproducing record comprising, in combination, a turntable having a flat surface, a marginal annular upstanding rim formed on said turntable, a strip of photographic film arranged in a loop and having formed thereon a continuous unbroken sound record, said loop being positioned on said rim with the record thereof overhanging said rim, a flat disk supported on said surface, a light sensitive coating positioned on the upper side of said disk, and optical means for projecting the sound record on said film onto said coating in the form of a continuous unbroken image circle.
3. A device for forming a sound-reproducing record comprising, in combination, a rotatable flat support, a recording disk positioned on said support, a recording surface on said disc, a strip of flexible material having formed thereon a sound record, said material being arranged in a loop and with the ends spliced together to form a continuous sound record, means on said support for holding said loop, said support being rotatable to move said loop and disk in synchronism, and means including optical members for projecting the record on said loop onto said surface in the form of a continuous unbroken sound image circle.
4. A device for forming a sound-reproducing record comprising, in combination, a turntable, a record receiving disk positioned on said turntable, a recording surface on said disc, a plurality of light transmitting sound-image carrying members individually and selectively positioned on said turntable, each member comprising a light transmitting strip with the ends thereof being spliced together to form a loop to provide a continuous sound track record, and means including optical members for progressively projecting the sound records of the various loops as separate independent sound track circles of continuous sound on said surface.

OTTO WITTEL.
